UNITED STATES PATENT OFFICE

2,608,457

WARDROBE STORAGE MEANS

Jules Scott Zibell, Decatur, Ga.

Application July 24, 1947, Serial No. 763,383

1 Claim. (Cl. 312—305)

1

The invention relates to wardrobe storage means and has as an object the provision of a device designed for maximum convenience in minimum space.

It is a further object to provide a combined closet, chiffonier, cupboard, tie rack and shelf space in a space such as that usually devoted to a closet in dwellings or apartments.

It is a further object to provide a structure providing the above-named conveniences that may be manufactured and sold as a unit ready for installation.

It is a further object to provide a structure that may be embodied in a self-contained furniture unit.

Further objects will appear from the following description when read with the accompanying drawings showing illustrative embodiments of the invention and wherein:

Figure 1 is a front elevation of the interior structure of the device, the door and front wall being omitted and the cylindrical casing shown in section;

Figure 2 is a horizontal section on line 2—2 of Figure 1 showing the front wall and door of a built-in device;

Figure 3 is a detail vertical section on line 3—3 of Figure 2;

Figure 4 is a detail vertical section of a stop device on an enlarged scale;

Figure 5 is a detail elevation of a drawer slide on an enlarged scale;

Figure 6 is a detail section on line 6—6 of Figure 5;

Figure 7 is a diagrammatic plan view of two built-in devices opening into different rooms;

Figure 8 is a diagrammatic view of a built-in unit as installed in a corner of a room;

Figure 9 is a diagrammatic view of a form of the invention marketable as a self complete article of furniture; and

Figure 10 is a like view of a form designed to fit a corner of an existing room.

As shown in Figures 1, 2 and 3, a structure is provided that may be installed in a house while under construction or in existing living quarters, in both instances the device comprising a cylindrical shell 11 having a portion of the full cylinder omitted and with the edges secured to a door frame 12, upon which is hung a door 13.

Within the cylinder 11 is shown a column 14 mounted to revolve in an upper bearing 15 from which it may be suspended. Desirably, however, a lower bearing 16 shown in dotted lines in Figure 1 is provided.

2

Carried by the column 14 there are shown upper and lower circular shelf members 17 and 18 and the top and bottom of the casing 11 are shown as closed by closures 19, 20.

To set off a space for drawers 21, there are shown partition members 22, 23 extending continuously between the shelves 17, 18 in a vertical direction and from the column 14 to the perimeters of the shelves. As shown the partitions 22, 23 are integral at their inner edges and formed into a channel at 24, shown as secured to the column 14.

To complete drawer spaces there are shown vertical partition members 25, 26 formed with square beads 27 at their front edges. The drawers 21 are shown as slidably mounted on the partitions 25, 26 by rollers and runners of a well known type 30 by means of which the drawers may be pulled well out of the enclosing space.

Desirably, and as shown, the upper drawer space is utilized as a cupboard shelf closed by a false drawer front 27a hinged to a shelf at 28, collapsible braces being provided as indicated at 29.

To support garment hangers, an arcuate rod 31 is shown in Figure 3 secured at its ends to the partitions 22, 23 as indicated at 32, 33.

To stiffen the partitions 22, 23, they are shown as formed at their free edges with bead members 34, 35.

For storage of neckties, racks 36, 37 are shown in the spaces at the sides of partitions 25, 26.

If desired, and as shown, a mirror 38 may be mounted on the back of the door 13. So equipped it is possible for a person to dress completely without leaving a position in front of the device.

When the door 13 is open the entire interior portions of the device may be turned, when the top and bottom shelves 17, 18, will travel in the dot and dash arc 48 of Figure 2 bringing the garments hanging upon rod 31, and articles on the rear of the shelves to positions of ready access.

To locate the revolving portion of the device in the position for closing the door 13, a yielding stop is shown in detail in Figure 4, comprising a casing 39 carried by the bottom shelf 18 and a spring pressed pin 40 which is designed to slip out of and into the socket 41 when the device is rotated.

The structure including the door frame 12 with the door ready hung is designed as an article of convenience. The partition framing 42, may

be built around the door frame and the casings 43 applied, when the device is ready for use.

Figure 7 shows two of the devices installed in positions for access from adjoining rooms, and Figure 8 illustrates a corner installation which may be used in an existing apartment.

In Figures 9 and 10 are shown forms of the invention illustrating its use as a self-contained article of furniture, one for a corner situation requiring no mechanical work for installation.

When so constructed, the outer walls 44, 45 make the inner cylindrical casing 11 unnecessary, but arcuate guide panels 46, 47 should be provided to guide swaying garments to the door opening. Otherwise, the structure of these forms may be identical with that already described.

Minor changes may be made in the physical embodiments of the invention within the scope of the appended claim without departing from the spirit of the invention.

I claim:

A wardrobe structure comprising: a fixed enclosing structure formed with a door frame; upper and lower closures for the structure; a column extending between said closures and revoluble relative thereto; upper and lower shelves formed as segments of circles greater than semicircles with the chord of each of less length than the opening of said frame, the chords of said segments standing in a common plane spaced within the plane of the door frame; a V-shaped partition secured at its apex to said column, extending vertically between said shelves and secured thereto with free edges of said partition adjacent to but spaced along the perimeters of said shelves from the jambs of said door frame; vertical partitions extending from the ends of

the respective chords rearwardly with their rear edges secured to the respective wings of the V-shaped partition and with their upper and lower ends secured to the respective segments, to define a space pentagonal in cross-section with its interior accessible through said door opening; horizontal means subdividing said pentagonal space into storage compartments; the arcs of said segments concentric with said column, and an arcuate garment hanger supporting rod with its ends secured to the wings of said partition.

JULIES SCOTT ZIBELL.
